UNITED STATES PATENT OFFICE

2,605,170

NITROGEN PRODUCTION

James P. Fugassi, Pittsburgh, Pa., assignor to the
United States of America as represented by the
Secretary of the Navy

Application May 6, 1946, Serial No. 667,555

1 Claim. (Cl. 23—220)

1

This invention pertains to a compact apparatus for producing nitrogen from air at high rates of flow and particularly to a device which will furnish a continuous supply of nitrogen containing two per cent or less of oxygen at high rates of flow.

Nitrogen is obtained by extracting oxygen from air. This is done by passing air over a heated metal such as copper. Oxygen in the air is removed by reaction with the metal. For copper, the equation for the reaction is $2\text{Cu} + \text{O}_2 \rightarrow 2\text{CuO}$. After a certain time interval when the rate of the reaction between the metal and oxygen becomes too slow, the resulting metal oxide is reduced by passing a hydrocarbon over the metal oxide. In the case of copper oxide, the equation for the reaction is

Of the products formed in the reduction stage, CO_2 and H_2O are discarded and the Cu is again available for use.

The object of this invention is the development of an apparatus which will perform the above oxidation and reduction processes efficiently and automatically.

Details of the invention are described in connection with the following drawing in which

Figure 1 is a schematic view of the apparatus; Fig. 2 is a diagrammatic view of the timing circuit; and Fig. 3 is a view of the nitrogen extraction apparatus as connected to the timer unit.

Experiments were conducted to develop the present apparatus in its final form. To perform the desired operations in the simplest form, two heated metal tubes, preferably copper, were selected and packed with small pieces of metal such as copper gauze, sponge copper, pieces of copper wire or clippings. A two-step cycle was utilized. In the first step, air was passed through the first tube while hydrocarbon was passing through the second tube. In the second step, the cycle was reversed after about one minute. The cycle was thus completed and then repeated.

The present apparatus is designed to perform the two steps of the cycle in a continuous automatic operation.

The apparatus as shown in Figure 1 uses a tube of the order of 0.5 inch in diameter and twenty feet long. Copper is preferred, although other metal tubes could be used if so desired. The tube 1 is coiled in a flat coil or helix, as shown, to conserve space and to obtain greatest efficiency. The tube is packed with a suitable

filler such as copper gauze which has been found to offer the greatest surface area.

An air inlet 2 and gasoline pipette 3 communicate with the intake of tube 1. The length of cycle and of each step is controlled automatically by an external clock device fitted with conventional electrical contacts which energize or de-energize solenoid valves 4 to perform the desired operations. Gasoline exhaust 5 and nitrogen outlet 6 are provided at the exhaust end of coil 1.

Nitrogen outlet 6 leads to a storage tank to be collected, or to its place of use. It will be apparent that proper control of the solenoid valves 15 at the inlet and outlet ends of tube 1 will result in automatic performance of the alternate oxidation and reduction steps in the cycle. Each step is of approximately one minute duration. The apparatus produces approximately one 15 cubic foot of nitrogen during the cycle containing less than two per cent oxygen. Figs. 2 and 3 illustrate the timing mechanism. The timer 10 is provided with a contact arm 11 adapted in rotation to make and break contact in sequence 20 with electrical contacts 12 separated by spaces 13. A battery 14 is circulated through the timer motor, the relay 15 and in parallel to the various contacts 12. Since the arm 11 is electrically conductive and the battery has connection to the 25 timer arm shaft end at 16, current flows through the relay 15 whenever the switch 17 is closed and arm 11 engages a contact 12, thereby energizing the relay and lifting armature 18 and valve arm 20 against the tension of spring 19 to its up position. On disengagement of arm 11 with contact 12 the relay is deenergized and the spring returns the armature to its normal down position.

As appears from Fig. 2, alternate movement of 30 the armature successively opens and closes one of each pair of valves 4, 4a and 4b being open while 4c and 4d are closed, and this position changing at the next cycle alternation to 4a and 4b being closed and 4c and 4d being open. Fig. 35 is illustrative also of this valve relationship, including the valve unit 4, and respective pair valves 4a, 4c and 4b, 4d. The respective closed and open positions of timer arm 11 are designated as M and O, the cycle alternations being designated as M—O—M—O etc.

Preferably tube 1 is heated in any desired manner to a temperature of 500° C. provided that complete oxidation of the hydrocarbon is not necessary. If complete oxidation of the hydrocarbon is required to lower hydrocarbon

consumption, the temperature should be raised to 700° C. Higher temperatures could not be used in the present apparatus because the reduction cycle is strongly exothermic as no thermostatic control is used. Because of the strong evolution of heat during the reduction cycle, localized superheating results so that in certain cases there is melting of the filling material and destruction of the catalytically active surface. Consequently, it is desirable to pass a stream of cold air over the outside of the tube when reduction is taking place. This can be thermostatically controlled.

When using a copper filling, it is desirable to treat the copper so that iron oxide is added. This can be done by soaking the copper filling in a concentrated aqueous solution of ferric nitrate for several hours. The copper filling is then removed, drained, and then heated to about 500° C. until nitrogen oxide fumes cease to be evolved. The filling after cooling is then ready for use. The addition of iron oxide is especially effective in increasing the efficiency of oxidation of the hydrocarbon. It has little or no effect on the rate of oxidation of copper by air.

For the reduction operation, any hydrocarbon that can be volatilized at temperatures up to 200° C. can be used. These include hydrocarbons such as cyclohexane, hexane, gasoline, and kerosene. It was found that one gallon of gasoline would furnish 3000-5000 cubic feet of nitrogen.

Although the present apparatus yields nitrogen up to one cubic foot a minute, it is obvious that the use of more tubes or larger tubes would permit any rate of flow desired.

Various experiments were conducted to determine the most efficient tube length and diameter, as well as tube filling. Tubes ranging in diameter from 0.5-4 inches in diameter were used and various filling materials were used. All units were heated with gas flames. The temperature was measured by attaching a thermocouple to the outer surface of the unit. Manual control was used to keep the temperature constant. After a period of operation, it was found that certain of these units contained solid globules of copper, which seems to indicate that during one of the cycles, overheating resulted in fusion of parts of the charge. Several charges

were made to minimize localized overheating. Tubes of smaller diameter offered the highest ratio of external surface area to volume. The tube of smaller diameter proved to be the most efficient with the least quantity of filling. Coarse copper gauze (14 mesh) proved to be the most satisfactory. This can be explained in that localized overheating of the active copper surface destroys the surface by fusion of the copper and results in clogging. The best results were obtained in using a bent copper tube twenty feet long and 0.5 inch in diameter. The tube contained tightly rolled copper gauze weighing two pounds and proved to be the most efficient one considering the weight of gauze used.

What is claimed is:

A method of producing nitrogen at reduced temperatures comprising heating to about 500° C. a single spirally coiled tubular chamber having closely adjacent coil sections and containing copper, passing air for approximately one minute through said chamber to oxidize the copper and obtain nitrogen, passing a hydrocarbon volatilizable at temperatures up to 200° C. through said chamber for approximately one minute to reduce the copper oxide, and continuously repeating said alternate air and hydrocarbon passages at a rate such that the exothermic heat due to the oxide reduction when combined with the applied heat and the heat due to radiation between said adjacent sections of said coil is sufficient to obtain nitrogen with an applied heat of about 500° C.
